UNITED STATES PATENT OFFICE

2,609,559

ROTARY BRUSH

Ruben O. Peterson, University Heights, Ohio, assignor to The Osborn Manufacturing Company, Cleveland, Ohio, a corporation of Ohio

Application March 5, 1947, Serial No. 732,445

36 Claims. (Cl. 15—182)

1

This invention relates, as indicated, to rotary brushes and more particularly to rotary brushes of the type which are adapted to be mounted on power driven mandrels and operated at high rates of speed.

Peterson Patent No. 2,303,386 discloses an improved form of brush strip which is adapted to continuous production and which may be circularized into any desired number of convolutions. While such strip is constructed in a manner firmly to secure the brush material therein nevertheless various problems are presented when such strip is to be formed into rotary brushes and mounted on a mandrel for high speed operation. When only one convolution is employed, thereby obtaining an annular section, it has been common practice to weld the channel back ends together and either to twist the retaining wire together or to bend the ends thereof into notches in the side walls of the channel. The welding operation is slow and expensive and is likely to injure the brush material. The bursting strength of the brush is not as high as desired.

Another method, long in use, has been to mount a single convolution, with slightly overlapping ends, on a mandrel or boss between two dished clamping plates, the inturned annular flanges of which overlie the outer edges of the channelform brush back. Such method, while greatly increasing the bursting strength, is ordinarily not suitable when a plurality of such annular sections are to be assembled in close side by side relation to form a larger cylindrical or "roller" brush since the brush material of adjacent sections will be kept from close lateral engagement and the brush will present a non-uniform surface. Furthermore, this method is not entirely suitable even in the case of a single convolution for the reason that the pressure required to make the inturned peripheral edges of the flange portions effective for holding the brush part against forces which act on it when rotated at high speeds excessively concentrates working stresses in the brush material at the point of contact with said inturned edges. Such concentrated working stresses cause excessive breakage of the brush material in use, especially when such material is flexed in a direction normal to the pressure. When this method is applied to several convolutions forming a unit brush the percentage of breakage of brush material is reduced by the increase of total brush material, but the amount of breakage caused adjacent to the inturned edges is nevertheless excessive.

2

As indicated, generally similar problems are presented when a plurality of convolutions are employed to form a helically wound brush. Here, of course, it is impossible to juxtapose the ends of the brush back for welding together and other means must be found for holding the convolutions tightly seated on the mandrel. The ends of the convolutions must not only be prevented from radially outward movement, but must also be held against circumferential slipping or unwinding which would cause the intermediate convolutions to come loose and bulge outwardly. Various types of end plates have been employed to which the ends of the strip could be secured but these are fussy to use and unsuitable where a number of helically wound sections are to be employed in association as they do not permit close enough assembling of the sections.

While a brush strip constructed in accordance with my aforesaid prior patent is greatly strengthened by means of the inturned teeth which hold the brush material retaining member in place it is nevertheless obvious that the bursting strength of a circularized section thus formed can be no greater than that of the channelform back.

It is, therefore, a primary object of my invention to provide means for mounting rotary brush elements upon a mandrel in a manner adapted greatly to increase the bursting strength of the brush.

A further object is to provide means for mounting a circularized brush element upon a mandrel effective to prevent unwinding thereof and to maintain such element tightly seated on the mandrel.

A further object is to provide means for joining together adjacent brush sections upon a mandrel to form a unitary brush.

Another object is to provide a rotary brush having a stepped or tapered face in which the bristle length will nevertheless be substantially uniform within reasonable limitations, thereby affording uniform brushing characteristics.

Still another object is to provide a circularized channelform brush strip mounted on a core portion in such manner as to provide a unitary rotary brush of high bursting strength and long life.

Other objects of this invention will appear as the description proceeds.

To the accomplishment of the foregoing and related ends, said invention then comprises the features hereinafter fully described and particu-

larly pointed out in the claims, the following description and the annexed drawings setting forth in detail certain illustrative embodiments of the invention, these being indicative, however, of but a few of the various ways in which the principle of the invention may be employed.

In said annexed drawings:

Fig. 1 is a sectional view axially of a rotary brush constructed in accordance with my invention;

Fig. 2 is an end view of such brush showing the end retaining flange;

Fig. 3 is a view similar to Fig. 1 but showing another means of locking the end flange in place;

Fig. 4 is an end view of the construction of Fig. 3;

Fig. 5 is a sectional view axially of a composite tapered brush in which the different brush elements have been assembled in accordance with my invention;

Fig. 6 is a sectional view along the line 6—6 on Fig. 5;

Fig. 7 is a view of a rotary brush assembly with the brush material cut away down to the channel-form brush back to show the disposition of the retaining members;

Fig. 8 is a perspective view of the end retaining member of Fig. 7;

Fig. 9 is a perspective view of the brush unit interconnecting member of Fig. 7;

Fig. 10 is a fragmentary elevational view of a retaining member provided with an additional outer row of teeth;

Fig. 11 is a sectional view taken along the line 11—11 on Fig. 10;

Fig. 12 is a fragmentary end elevational view of a unitary rotary brush assembly formed in accordance with my invention;

Fig. 13 is a sectional view of such brush taken along the line 13—13 on Fig. 12;

Fig. 14 is a similar sectional view but showing another embodiment wherein a larger number of turns of brush strip are mounted on a core portion; and

Fig. 15 is a similar sectional view of an embodiment in which but a single turn is thus mounted.

Referring now more particularly to such drawings, and especially Figs. 1 and 2 thereof, the brush of this invention may comprise one or more turns of a circularized brush strip mounted upon a mandrel 1. As illustrated, such brush strip may be formed in the manner taught in my Patent No. 2,303,386 comprising radially extending brush material 2 held within a channel-form back 3 by means of a retaining member such as wire 4 which is itself firmly held within such channel by means of overlying teeth 5 punched in from the respective sides of such channel-form back. Fig. 1 shows a plurality of such brush elements assembled upon the mandrel, each element comprising a plurality of helical turns of such brush strip. Shown interposed between two such elements is a flat annular retaining ring 6 seated upon the mandrel and provided with a plurality of circularly disposed teeth 7 projecting to each side in an axial direction. Such teeth are provided with inner inclined edges and are radially spaced to indent and bear against the respective peripheral edges of the endmost turns of such helically wound channel-form brush back. It will thus be seen that, when such circularized brush elements are assembled with the above-described retaining member therebetween and laterally compressed, the inclined edges of the teeth of such retaining member will cam

down the respective adjacent edges of the channel-form brush back, thereby firmly seating such brush backs upon the mandrel and upon being thus tightly compressed, such teeth will indent or notch the edges of the brush back thereby locking the adjacent helically wound brush elements together into one unit.

As also shown in Fig. 1, such retaining member may desirably be secured against rotation relative to the mandrel as by means of an inwardly projecting tab 8 welded thereto and adapted to extend into a keyway 9 in such mandrel. In this manner a cylindrical rotary brush of considerable length may be assembled of a plurality of helically wound brush elements, such elements not only being interlocked and firmly seated upon the mandrel through action of such retaining member but also secured against possibility of slipping and rotation relative to the mandrel.

The outer ends of the brush may similarly be secured by means of an annular retaining member 10 provided with a plurality of circularly disposed teeth 11 projecting to one side only and similarly overlying and indenting the outer peripheral edge of the channel-form back. Such endmost retaining member will also desirably be provided with a locking tab or key 12 fitting in keyway 9. A nut 13 is adapted to be screwed on to the threaded end of the mandrel to bear against the endmost retaining member 10 and hold the brush elements in assembled relation.

Referring now to Figs. 3 and 4 an alternative means for securing the end retaining member is there illustrated. In this example such end retaining member 14 is provided with an axially extending flange 15 at its inner periphery adapted to be seated upon the mandrel 1. Such flange is periodically expanded as at 16 to permit a hardened pin 17 provided with a self-tapping thread to be driven into the opening formed thereby thus firmly securing such retaining member in place.

As shown in both Figs. 1 and 3 such endmost retaining member will desirably have an annular inwardly directed bulged portion 18 adjacent its outer periphery adapted to compress the brush material of the endmost turn of the circularized brush back since, of course, such brush material is not supported to this side by the material of an adjoining turn.

The retaining member of this invention may not only be employed to interlock adjoining brush elements of the same diameter, as shown in Fig. 1, but may also be employed where it is desired to assemble brush elements of varying diameters. It is ordinarily not desirable to form a cylindrical brush having a longitudinally stepped face by employing a plurality of turns of a brush strip having brush material of a uniform length and trimming down desired portions of the brush material to obtain a brush of varying diameter. Due to the difference in length of the brush material extending from the brush back at different points along the length of such a brush very different brushing characteristics would be obtained with resultant non-uniform effect upon the work being brushed.

As shown in Figs. 5 and 6, by employing a mandrel comprising cylindrical portions of different diameters 19 and 20 this difficulty may be overcome. A brush having a stepped face, as indicated in dot-and-dash line on such Fig. 5, will thus result. This brush may then be trimmed to the tapered contour shown without any very

great variation in bristle length resulting from one end to the other of the brush. In order to lock two such adjoining brush elements together an annular retaining ring 21 is provided seated on the smaller diameter portion of the mandrel and provided with circularly arranged teeth projecting axially in each direction, the teeth 22 being less radially outwardly spaced than teeth 23 in order to indent and bear against the outer peripheral edge of the channelform brush back mounted on portion 20 while teeth 23 are adapted to indent and bear against the edge of the brush back mounted upon the larger mandrel portion 19.

While it is common practice to laterally compress a helically wound rotary brush element to cause such element to conform to end flanges normal to the axis of the mandrel, it is advantageous for certain purposes, as well as more convenient, to permit such helically wound elements to retain their normal offset relationship when mounted upon the mandrel. For this purpose a particular modification of the above-described annular retaining member is illustrated in Figs. 7-9 inclusive. A flat annular retaining ring 24 (see Fig. 8) is seated on the mandrel 1 at one end of the helically wound brush element provided with a plurality of circularly arranged teeth 25 adapted to indent and bear against a peripheral edge of the brush back, portion 26 of such retaining member being axially offset to conform to the end 27 of the helically wound brush element. End nut 13 is adapted to hold such end retaining member firmly in place and a key 28 may desirably be provided on such retaining member adapted to fit in keyway 29 of the mandrel to lock the brush element positively against rotation relative thereto. The right-hand portion of Fig. 7 illustrates a form of retaining member adapted to be interposed between two adjoining helically wound brush elements. This retaining member 30 resembles member 24 except that it is, of course, provided with teeth 31 projecting to each side to engage and bear against the adjacent peripheral edges of the adjacent endmost turns of the helically wound channelform brush backs. Member 30 also differs from member 24 in that it is in the form of a helix, an offset 32 equal to the width of the brush back being provided whereby such retaining member may conform to the opposed ends 33 and 34 of such brush backs.

In rotary brushes of the general type described above it has been found that the brush material generally first fails and breaks at the point where the same leaves the channelform back. At this point the material is tightly compressed and in ordinary use it is at this point where most of the flexure of the individual bristles takes place. In order to extend the length of that portion of the brush bristle at which such flexure takes place, and thereby increase the life of the brush, it has been found desirable to provide an additional outer radially spaced row of teeth on my new retaining members which have the effect, particularly in cooperation with the inner row of teeth which bear upon the edge of the channelform brush back, of causing such flexure to be distributed along that portion of the bristle length lying between such two rows of teeth. These additional teeth may be employed on both my end retaining members and my intermediate retaining members.

Figs. 10 and 11 show fragmentary detail views of such an intermediate member 35 provided with

an inner row of teeth 36 and an outer row of teeth 37, it being noted that such teeth are arranged in radially disposed pairs projecting in the same directions. The inner row of teeth 36 is, of course, adapted to indent and bear against the edge of the channelform brush back.

While the retaining members of my invention are particularly valuable for use in conjunction with one or more circularized turns of a brush strip the ends of which are not joined to form a continuous annulus, such retaining members may nevertheless be employed to great advantage with ordinary rotary brush sections having continuous annular brush backs. In such case the teeth of the retaining member which bear upon the outer periphery of the brush back serve greatly to increase the bursting strength of such brush and an outer row of teeth such as 37 will similarly increase the life of the brush material by causing the flexure of the same to be more generally distributed. The form of retaining member provided with teeth extending to either side thereof, as shown in Fig. 1 for example, may likewise be employed to reinforce and interlock such adjoining annular sections.

The brush material may be of any of the types employed in rotary brushes including Tampico fiber, wire, cord, and strands of synthetic plastic.

As shown in Figs. 12 to 15 inclusive, the principle of my invention may be employed not only in mounting rotary brush elements directly on a mandrel but also in embodiments wherein such elements are mounted on separate cylindrical core portions which in turn may be slid upon a mandrel or supported by conventional adapters. In the form illustrated in Figs. 12 and 13 the annular retaining members 38 and 39 are provided with opposed cylindrical core portions 40 and 41 on which the turns of brush strip 3 are seated. Radially inwardly directed flanges 42 and 43 are joined by upset portions 44 which serve to rivet the two together, holding them in close compressive engagement with the circularized brush element. Teeth 45 and 46 serve in the same manner as teeth 11 in the Fig. 1 embodiment to indent and bear against the edge of the channelform back 3.

Fig. 14 shows two end retaining members 47 and 48 generally similar to member 10 of Fig. 1 but mounted on a length of tubing 49 and held in place by upset ends 50 and 51. The helical convolutions of brush strip retained therebetween in compressed relationship are held in place by teeth 52 and 53 arranged in like manner to the teeth of the Fig. 1 embodiment. Fig. 15 shows a single convolution clamped between two retaining members 54 and 55, each of which will desirably be provided with teeth such as 56. The inner peripheral flange 57 of member 54 is upset to lock the two members together to form a unitary rotary brush wherein the channelform back 3 of the brush strip is seated on opposed cylindrical core portions of such members.

It will be apparent from the foregoing that rotary brush elements may be mounted in accordance with my invention either directly upon a solid or tubular mandrel or upon separate core portions formed, for example, by axial annular extensions of the retaining members. The mandrel or other core will ordinarily be cylindrical in form although it may be of other cross section, such as octagonal, if desired. When an annular rotary brush element comprising one or more turns of brush strip is mounted as taught herein and a number are assembled to provide a

composite brush it is readily apparent that should one portion of the brush be damaged it may be replaced without having to discard the entire brush.

Other modes of applying the principle of the invention may be employed, change being made as regards the details described, provided the features stated in any of the following claims or the equivalent of such be employed.

I therefore particularly point out and distinctly claim as my invention:

1. In combination, a mandrel; a rotary brush element seated on said mandrel, said element comprising a plurality of helical turns of a channelform brush back having teeth punched inwardly from the sides thereof, a retaining member disposed longitudinally within said channelform back and held in place beneath said teeth, and brush material held in said channelform back by said retaining member; annular retaining members seated on said mandrel to either side of said helically wound brush element and provided with a plurality of circularly disposed teeth projecting in an axial direction adapted to indent and bear against the respective peripheral edges of the endmost turns of said helically wound channelform brush back; and a nut threaded on the end of said mandrel operative, upon being tightened, to bear against one of said toothed annular retaining members to force such teeth into such engagement with the edge of said brush back.

2. In combination, a cylindrical core; a rotary brush element seated on said core, said element comprising a plurality of helical turns of a channelform brush back having teeth punched inwardly from the sides thereof, a retaining member disposed longitudinally within said channelform back and held in place beneath said teeth, and brush material held in said channelform back by said retaining member; and annular retaining members seated on said core to either side of said helically wound brush element and provided with a plurality of circularly disposed teeth projecting in an axial direction indenting and bearing against the respective peripheral edges of the endmost turns of said helically wound channelform brush back.

3. In combination, a cylindrical core; an annular rotary brush element seated on said core, said element comprising a circularized channelform back having teeth punched inwardly from the sides thereof, a retaining member disposed longitudinally within said channelform back and held in place beneath said teeth, and brush material held in said channelform back by said retaining member; and annular retaining members seated on said core to either side of said element and provided with a plurality of circularly disposed teeth projecting in an axial direction and indenting and bearing against the respective peripheral edges of said channelform back.

4. In combination, a cylindrical core, a rotary brush element seated on said core, said element comprising a plurality of helical turns of a circularized channelform brush back having radially extending brush material secured therein, and annular retaining members seated on said core to either side of said helically wound brush element and provided with a plurality of circularly disposed teeth projecting in an axial direction indenting and bearing against the respective peripheral edges of the endmost turns of said helically wound channelform brush back.

5. In combination, a cylindrical core, a ro-

tary brush element seated on said core, said element comprising a plurality of helical turns of a circularized channelform brush back having radially extending brush material secured therein, and an annular retaining member seated on said core and provided with a plurality of circularly disposed teeth projecting in an axial direction indenting and bearing against a peripheral edge of such brush back.

6. In combination, a cylindrical core, an annular rotary brush element seated on said core, said element comprising a circularized channelform brush back having radially extending brush material secured therein, and annular retaining members seated on said core to either side of said element and provided with a plurality of circularly disposed teeth projecting in an axial direction indenting and bearing against the respective peripheral edges of such channelform brush back.

7. A brush comprising a cylindrical core portion, an annular rotary brush element having a back seated on said core portion, an annular retaining portion provided with a plurality of circularly disposed teeth projecting in an axial direction, and means holding said retaining portion in close relationship with said brush element with such teeth indenting and bearing against the outer periphery of the back of said brush element.

8. In combination, a mandrel, an annular rotary brush element having a back seated on said mandrel, and an annular retaining member seated on said mandrel and provided with a plurality of circularly disposed teeth projecting in an axial direction and indenting and bearing against the outer periphery of such back of said brush element.

9. In combination, a cylindrical core, an annular rotary brush section seated on said core, said section comprising a circularized channelform brush back having radially extending brush material secured therein, and an annular retaining member seated on said core and provided with a plurality of teeth projecting in an axial direction overlying and bearing against an outer peripheral edge of such channelform back, said teeth being flat and thin and lying in radial planes to facilitate penetration of such brush material.

10. In combination, a core, a rotary brush section seated on said core, said section comprising a circularized channelform back having radially extending brush material secured therein, and an annular retaining member seated on said mandrel provided with a thin flat sheet material tooth projecting in an axial direction and lying in a radial plane adapted to overlie and bear edgewise against an outer peripheral edge of such channelform back.

11. In combination, a core, a rotary brush section seated on said core, said section comprising a circularized channelform back having radially extending brush material secured therein, an annular retaining member seated on said core provided with a thin flat tooth projecting in an axial direction and lying in a radial plane, said tooth indenting and bearing against an outer peripheral edge of such channelform back, and means adapted to secure said retaining member against rotation relative to said core.

12. In combination, a mandrel, a rotary brush element seated on said mandrel, said element comprising a circularized channelform back having radially extending brush material secured

therein, an annular retaining member seated on said mandrel provided with a plurality of teeth projecting in an axial direction and indenting and bearing against an outer peripheral edge of such channelform back, a keyway in said mandrel, and a projection on said retaining member adapted to fit in said keyway to secure said retaining member against rotation relative to said mandrel.

13. In combination, a core, a rotary brush element seated on said core, said element comprising a plurality of helical turns of a circularized channelform brush back having radially extending brush material secured therein, annular retaining members seated on said core to either side of said element provided with a plurality of teeth projecting in an axial direction and indenting and bearing against the respective peripheral edges of the endmost turns of said helically wound channelform brush back, and means adapted to secure said retaining members against rotation relative to said core.

14. In combination, a core, two annular rotary brush sections having backs seated on said core, and an annular retaining member seated on said core between said sections and provided with teeth projecting to each side in an axial direction and overlying and bearing against the respective outer peripheries of such backs of said brush sections.

15. In combination, a cylindrical core, two annular rotary brush sections seated on said core, said sections comprising a circularized channelform back having radially extending brush material secured therein, and an annular retaining member seated on said core between said sections and provided with teeth projecting to each side in an axial direction indenting and bearing against the adjacent peripheral edges of such respective channelform brush backs.

16. In combination, a cylindrical core, two rotary brush elements seated on said core, said elements comprising a plurality of helical turns of a channelform brush back having radially extending brush material secured therein, and an annular retaining member seated on said core between said elements and provided with teeth projecting to each side in an axial direction indenting and bearing against the adjacent peripheral edges of the adjacent endmost turns of said helically wound channelform brush backs.

17. In combination, a core, two rotary brush elements seated on said core, said elements comprising a plurality of helical turns of a channelform brush back having radially extending brush material secured therein, an annular retaining member seated on said core between said elements and provided with teeth projecting to each side in an axial direction indenting and bearing against the adjacent peripheral edges of the adjacent endmost turns of said helically wound channelform brush backs, and means adapted to secure said retaining member against rotation relative to said core.

18. In combination, a core comprising cylindrical portions of different diameters, rotary brush elements having backs seated on such portions, and an annular retaining member seated on said core between said elements and provided with teeth projecting to each side in an axial direction, the teeth on each side being respectively radially spaced to overlie and bear against the corresponding adjacent outer peripheries of such backs of said brush elements.

19. In combination, a mandrel comprising cy-

lindrical portions of different diameters, rotary brush elements respectively seated on such portions, said elements each comprising a plurality of helical turns of a channelform back having radially extending brush material secured therein, and an annular retaining ring seated on said mandrel between said elements and provided with teeth projecting to each side in an axial direction, the teeth on each side being respectively radially spaced to indent and bear against the corresponding adjacent peripheral edges of the adjacent endmost turns of said helically wound channelform brush backs.

20. In combination, a mandrel comprising two cylindrical portions of greater and smaller diameter, rotary brush elements respectively seated on such portions, said elements each comprising a plurality of helical turns of a channelform back having radially extending brush material secured therein, such brush material being trimmed to provide a continuous taper from the greater to the smaller end of said mandrel, and an annular retaining ring seated on said mandrel between said elements and provided with teeth projecting to each side in an axial direction, the teeth on each side being respectively radially spaced to indent and bear against the corresponding adjacent peripheral edges of the adjacent endmost turns of said helically wound channelform brush backs.

21. As a new article of manufacture, means for securing a rotary brush element on a mandrel comprising a flat annular ring adapted to be seated on such mandrel, a plurality of circularly arranged teeth on said ring projecting to each side in an axial direction, all said teeth on one side being uniformly further radially spaced from the central opening of said ring than said teeth on the other side, and an inwardly directed projection on said ring adapted to fit in a key way in such mandrel.

22. In combination, a core, a rotary brush element seated on said core, said element comprising a plurality of helical turns of a circularized channelform brush back having radially extending brush material secured therein, and a flat annular retaining ring seated on said core and provided with a plurality of circularly arranged teeth projecting in an axial direction and indenting and bearing against a peripheral edge of such brush back, a portion of said ring being axially offset to conform to the end of said helically wound brush element.

23. In combination, a core, a rotary brush element seated on said core, said element comprising a plurality of helical turns of a circularized channelform brush back having radially extending brush material secured therein, a flat annular retaining ring seated on said core and provided with a plurality of circularly arranged teeth projecting in an axial direction and indenting and bearing against a peripheral edge of such brush back, a portion of said ring being axially offset to conform to the end of said helically wound brush element, and means adapted to prevent rotation of said retaining ring relative to said core.

24. In combination, a core, two rotary brush elements seated on said core, said elements comprising a plurality of helical turns of a channelform brush back having radially extending brush materials secured therein, and a flat annular retaining ring seated on said core between said elements and provided with teeth projecting to each side in an axial direction indenting and bearing

11

against the adjacent peripheral edges of the adjacent endmost turns of said helically wound channelform brush backs, said retaining ring being axially offset to conform to the opposed ends of said backs.

25. As a new article of manufacture, means for joining and securing two helically wound rotary brush strip elements having channelform backs wound on a mandrel comprising a thin flat annular ring adapted to be seated on such mandrel therebetween and provided with a plurality of circularly arranged teeth projecting to each side in an axial direction and spaced from the central opening of said ring, said ring being offset to conform to both of the opposed endmost helical convolutions of said rotary brush elements when interposed therebetween.

26. In combination, a core, an annular rotary brush element having a back seated on said core, and an annular retaining member provided with a plurality of teeth projecting in an axial direction and overlying and bearing against the outer periphery of such back of said brush element, said retaining member being further provided with additional teeth spaced radially outwardly from said first-named teeth and adapted to penetrate the brush material of said element intermediate said first-named teeth and the outer brushing surface of said element.

27. In combination, a core, an annular rotary brush element seated on said core, said element comprising a circularized channelform brush back having radially extending brush material secured therein, and an annular retaining member seated on said core and provided with a plurality of circularly arranged teeth projecting in an axial direction indenting and bearing against an adjacent peripheral edge of said channelform brush back, said retaining member being further provided with additional teeth spaced outwardly from said first named teeth and adapted to penetrate such brush material intermediate said first named teeth and the outer brushing surface of said element.

28. In combination, a core, an annular rotary brush element seated on said core, said element comprising a circularized channelform brush back having radially extending brush material secured therein, and an annular retaining member seated on said core and provided with a plurality of circularly arranged teeth projecting in an axial direction and closely overlying an adjacent turn of said brush back, said retaining member being further provided with additional teeth spaced outwardly from said first named teeth and adapted to penetrate such brush material intermediate said first named teeth and the outer brushing surface of said element.

29. In combination, a core, two annular rotary brush elements seated on said core, said sections comprising a circularized channel form back having radially extending brush material secured therein, and an annular retaining member seated on said core between said elements and provided with teeth projecting to each side in an axial direction and indenting and bearing against the adjacent peripheral edges of such respective channelform brush backs, said retaining member being further provided with additional teeth spaced outwardly from said first named teeth and adapted to penetrate such brush material intermediate said first named teeth and the outer brushing surface of said element.

30. A brush comprising two supporting members having opposed centrally disposed cylind-

12

rical core portions and spaced end retaining portions, an annular rotary brush element seated on such core portions between such end retaining portions, said element comprising a circular channelform back having radially extending brush material retained therein, a plurality of circularly disposed teeth projecting in an axial direction from such end portions and indenting and bearing against outer peripheral edges of such channelform back, and means holding said two supporting members in close compressive relationship to said brush element.

31. A brush comprising two supporting members having opposed centrally disposed cylindrical core portions and spaced end retaining portions, an annular rotary brush element seated on such core portions between such end retaining portions, a plurality of circularly disposed teeth projecting in an axial direction from such end portions and indenting and bearing against the outer periphery of the brush back of said element, and means holding said two supporting members in close compressive relationship to said brush element.

32. A brush comprising two supporting members having opposed centrally disposed core portions and spaced end retaining portions, an annular rotary brush element having a back seated on such core portions between such end retaining portions, a plurality of circularly disposed teeth projecting in an axial direction from at least one such end portion and overlying and bearing against the outer periphery of such back of said brush element, and means holding said two supporting members in close compressive relationship to said brush element.

33. In combination, a cylindrical core, a rotary brush element seated on said core, an annular retaining member seated on said core and engaging said brush element, an axially extending flanged portion at the inner periphery of said annular retaining member, and a threaded pin driven between said flanged portion and said core to lock said retaining member in desired position.

34. As a new article of manufacture, means for securing a helically wound rotary brush element on a supporting core, such element comprising an elongated back with a layer of brush material extending therefrom, said securing means comprising a thin flat annular ring having a central aperture therethrough for seating said ring on such core, and a plurality of thin flat teeth on said ring lying in radial planes and extending in a direction parallel to the axis of said ring, said teeth being uniformly spaced radially outwardly from such center aperture with their radially inner edges inclined to overlie and bear against the outer peripheral edge of such helically wound brush back, and said flat annular ring being of helical conformation to fit closely against a corresponding end of such helically wound brush element on such core.

35. A brush comprising a core portion, an annular rotary brush element having a back seated on said core portion, and a retaining portion provided with a plurality of circularly disposed thin flat teeth projecting in an axial direction which overlie and bear against the outer periphery of such back of said brush element, said thin flat teeth themselves lying in radial planes and therefore presenting their thin dimension substantially parallel to the adjacent strands of brush material to facilitate penetration there-

36. In combination, a core portion, an annular rotary brush element having a back seated on said core, and an annular retaining member provided with a plurality of thin flat wheel material teeth projecting in an axial direction and lying in radial planes, said teeth being spaced to overlie and bear edgewise against the outer periphery of said back of said brush element.

RUBEN O. PETERSON.
